C. E. BUELL.
 COMBINED TELEPHONE AND FIRE ALARM SYSTEM.
 APPLICATION FILED APR. 9, 1901.

903,153.

Patented Nov. 3, 1908.

UNITED STATES PATENT OFFICE.

CHARLES E. BUELL, OF NORTH PLAINFIELD, NEW JERSEY, ASSIGNOR TO GENERAL FIRE EXTINGUISHER COMPANY, OF NEW YORK, N. Y., A CORPORATION OF NEW YORK.

COMBINED TELEPHONE AND FIRE-ALARM SYSTEM.

No. 903,153.

Specification of Letters Patent.

Patented Nov. 3, 1908.

Original application filed May 10, 1900, Serial No. 16,239. Divided and this application filed April 9, 1901; Serial No. 55,105.

To all whom it may concern:

Be it known that I, CHARLES E. BUELL, of North Plainfield, Somerset county, State of New Jersey, have invented Improvements in Combined Telephone and Fire-Alarm Systems, of which the following is a specification, the same being a division of my application entitled "Combined fire alarm and extinguishing systems", filed May 10, 1900, and serially numbered 16,239.

The invention relates to the combination, with a telephone system, of alarm mechanism connected with an automatic sprinkler system whereby the sprinkler system alarm or alarms will be sent over the telephone circuit to the telephone central station.

The invention consists in the combination, with the telephone system and the sprinkler system, of means whereby when a sprinkler opens a definite number signal will be sent over the telephone circuit to the central station designating the location of the place where the sprinkler has opened.

The invention further consists in the combination, with the telephone system and the sprinkler system, of a main valve for the sprinkler system, and means whereby when said valve is moved from its position of fully open the same definite number signal will likewise be sent over the telephone circuit to the central station.

The invention further consists in the combination, with the telephone system and the sprinkler system, of a main valve for said sprinkler system, of means whereby when said valve is moved from its position of fully open a definite number signal will be sent over the telephone circuit to the central station and a supplemental or secondary alarm will also be sent to said central station.

The invention further consists in the combination and arrangement of parts herein-after described and claimed.

Referring to the drawings, Figure 1 represents partly in diagrammatic form a portion of an automatic sprinkler system with the alarm mechanism thereof combined with the telephone system. Figs. 2 and 3 represent details of the alarm mechanism.

The portion of the sprinkler system shown in Fig. 1 comprises the riser P with the hand operated valve v in the valve casing V for controlling the supply of water thereto, and

with a distributing pipe p leading therefrom and provided with automatic sprinklers S.

In addition to the main valve v and between said valve and the main supply pipe M S is a valve R V for controlling the operation of the alarm mechanism. Said valve R V, which is shown as a swinging valve, is adapted to close the open end f of the pipe p', which pipe p' leads to and is connected with the water motor M. Said pipe p' is extended beyond the water motor M and is provided at its upper end with a pressure gage G, said gage being insulated from the pipe as shown at g. Said pressure gage G is provided with a contact e adapted to be electrically engaged by the pointer of said gage. The sprinkler system shown is what is known as a wet pipe system in which the water normally stands under pressure in the riser p and the distributing pipes leading therefrom. The valve R V has a larger area exposed to the water pressure on the side toward the sprinklers and consequently said valve will, by reason of such differing area, be normally held in its closed position by the water pressure in the distributing pipes. Preferably a small hole is formed through the valve R V, as shown, for the purpose of accommodating any slight changes of pressure in the system.

The valve o v connected to or movable with the main valve v is adapted to normally close a vent or opening from the valve casing V. A check-valve e v is preferably employed, said valve being located beyond the main valve v, as shown in dotted lines in Fig. 1.

With the construction above described, whenever a sprinkler opens, the flow of water therefrom will cause a reduction of pressure in the riser P and corresponding reduction of pressure on the sprinkler side of the valve R V, and so that the water pressure on the supply side of said valve will operate to open the valve, thereby admitting the water-pressure from the supply-pipe to the pipe p' and through the same to the water-motor to operate the same. It will also be seen that whenever the main valve v is moved from its fully open position, and so as to thereby open the valve o v, the flow of water from the valve-casing through the opening which is normally closed by said

valve v will likewise cause a similar reduction of pressure on the sprinkler side of the valve R V and a second opening of said valve and admission of the water-pressure to the pipe p' to operate the water-motor M .

D is a generator the armature of which is carried by the shaft a of the motor M , and so that when said motor is operated by the flow of water thereto said armature will be rotated and a current of electricity generated by said generator.

S b represents a switch-board at the telephone central station with the usual connections and circuits leading therefrom, including enunciators as shown. The switch-board S b is of the usual construction and is shown as composed of a series of vertical and horizontal cross-bars with plug-holes at their intersections adapted to receive metal plugs by which any desired connection may be made between the radiating lines.

The circuit 1, 1, leads to the telephone T located at the building where the sprinkler system shown is installed. The telephone circuit which connects the telephone T with the switch-board at the central station normally leads through the pressure gage G by reason of the contact of the pointer with the contact e , which contact is maintained so long as there is no pressure in pipe p' . The generator D is included in a branch circuit z z leading from the main telephone circuit, said branch circuit z z being normally open. Normally the generator D is shunted out of the telephone circuit by means of the short path which leads through the pressure-gage G .

Mounted on the motor-shaft a is a friction-wheel w which engages a friction-wheel w' suitably supported in relation thereto and carrying a number wheel w^2 provided with projections e' . Mounted in a suitable position to be engaged by said projections e' is a spring s' , as shown in Fig. 2, connected to one of the wires z , while connected to the other wire z is a contact j c , the arrangement being such that when the number wheel is rotated the projections e' will successively move the spring s' into engagement with the contact j c and thereby close the branch circuit in which the generator is located. Preferably a resistance R is employed to facilitate the building up of a current by the generator when the water-motor is started.

In place of the number wheel w^2 the cylinder of a phonograph may be connected with the disk w' with the pointer for engaging said phonograph cylinder secured to the spring s' and so that said phonograph cylinder will, by its rotation, operate to vary the pressure between the carbon electrodes c c' , the electrode c being carried by the spring s and the electrode c' being adjustably mounted so as to be adjusted with relation to the

electrode c by means of the adjusting screw j c .

A line leads from one of the wires z to the spring s which is arranged to be engaged by an insulated projection K on the handle H of the valve v when said valve is in its fully open position, as shown in Fig. 1. The contact i is arranged in proximity to the spring s , said contact being connected by a wire with the water-pipe and thereby grounded. A grounded wire b' is connected with the switch-board at the telephone station, which said grounded line includes a bell b . With this arrangement, whenever the handle H is moved to turn the valve from its fully open position, the projection K will be moved from beneath the spring s , which will thereby be permitted to come in contact with the contact i and thereby close the grounded line formed by one side of the main telephone circuit and thereby ring the bell b .

The operation of the apparatus above described is as follows: Whenever a sprinkler opens, or whenever the valve v is moved from its fully open position, the valve R V will be opened by the water-pressure on the supply side to permit the flow of water through the pipe p to operate the water-motor M and thereby start the generator D and also rotate the number wheel w^2 . The water-pressure in the pipe p' will serve to move the pointer on the pressure-gage G out of contact with the contact e which will serve to throw the generator into the telephone circuit. The current generated by the generator will flow over the telephone circuit to the central station and will there operate the drop of the enunciator connected with that circuit, and the operator at the central station will hear through the receiver the number signals sent over the line by the generator under the action of the number wheel. As such number signals will be thus sent over the telephone circuit and heard on the receiver at the central station, both when the sprinkler opens and when the main valve is moved from its position of fully open, it is desirable that the operator should know whether the alarm so sent is a sprinkler alarm or a valve-alarm, and for this purpose the secondary grounded circuit above described is employed, and so that when the alarm sent over the telephone circuit is a valve-alarm this fact will be denoted by the ringing of the bell b which is effected by the closing of the grounded battery circuit b' by the contact of the spring s with the contact i .

When the arrangement shown in Fig. 3 is employed in place of the number wheel any words which may be impressed upon the phonograph cylinder will, by the variation in pressure between the constant contact electrodes, be caused to be transmitted over the wires z z and thence over the main tele-

phone circuit to the central station and where they will be heard upon the receiver at said station. It will be understood that, when the phonograph is used, central is called by the generator D in the same manner as when the number-wheel is used.

What I claim as my invention and desire to secure by Letters Patent is:

1. The combination, with a telephone circuit, of an automatic sprinkler system and an alarm mechanism connected with said sprinkler system and adapted to be operated by a reduction of pressure in said system, said alarm mechanism embodying a generator adapted to be included in the telephone circuit, and means for causing a number signal to be sent over said telephone circuit under the action of said generator.
2. The combination, with a telephone circuit, of an automatic sprinkler system, and an alarm mechanism connected with said sprinkler system and adapted to be operated by the opening of a sprinkler, said alarm mechanism embodying a generator adapted to be included in the telephone circuit, and means for causing a number signal to be sent over said telephone circuit under the action of said generator.
3. The combination, with a telephone circuit, of an automatic sprinkler system, and an alarm mechanism connected with said sprinkler system and adapted to be operated by the movement of the main valve from a position of fully open, said alarm mechanism embodying a generator adapted to be included in the telephone circuit, and means for causing a number signal to be sent over

said telephone circuit under the action of said generator.

4. The combination, with a telephone circuit, of an automatic sprinkler system, and an alarm mechanism connected with said sprinkler system and adapted to be operated by the opening of a sprinkler or by the movement of the main valve from its position of fully open, said alarm mechanism embodying a generator adapted to be included in the telephone circuit, and means for causing a number signal to be sent over said telephone circuit under the action of said generator.

5. The combination, with a telephone circuit, of an automatic sprinkler system, and an alarm mechanism adapted to send number signals over said telephone circuit when the main valve is moved from its fully open position, and a second circuit adapted to send a supplemental alarm when said main valve is thus moved.

6. The combination, with a telephone circuit, of an automatic sprinkler system, and an alarm mechanism connected with said sprinkler system and adapted to be operated by a reduction of pressure in said system, said alarm mechanism embodying a motor, a generator operated by said motor and adapted to be included in the telephone circuit, and a number wheel operated by said motor for causing a signal to be sent over said telephone circuit by the action of said generator.
